Primary Examiner—Prabhakar G. Deshmukh

[57] **CLAIM**

The ornamental design for a backpack for carrying a French easel, as shown and described.

DESCRIPTION

FIG. 1 is a front perspective view of a backpack for carrying a French easel showing my new design;

FIG. 2 is a rear perspective view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of easel is for illustrative purpose only and forms no part of the claim.
